UNITED STATES PATENT OFFICE.

ALPHONSO C. WILLIAMS, OF CAMBRIDGEPORT, MASSACHUSETTS.

PAPER BOTTLE.

SPECIFICATION forming part of Letters Patent No. 250,469, dated December 6, 1881.

Application filed July 11, 1881. (No model.)

To all whom it may concern:

Be it known that I, ALPHONSO C. WILLIAMS, of Cambridgeport, county of Middlesex, and State of Massachusetts, have invented a new 5 and useful Improvement in Paper Bottles, of which the following description, in connection with the accompanying drawings, is a specification.

This invention has for its object the production from paper of a bottle-like receptacle for liquids or solids or dry substances, such as baking and other powders. A bottle of this 10 class is lighter than and cannot be broken as easily as one of glass, and is cheaper than 15 glass, wood, or tin.

The invention consists in a paper bottle having a thicker paper-board top to fit the sides, and provided with an opening for a stopper, combined with a paper stopper having a tubular 20 neck to fit in said opening, and a polygonal head, all as hereinafter specified and claimed.

Figure 1 represents, in elevation, a paper bottle embodying my invention; Fig. 2, a vertical section thereof. Fig. 3 shows, on a smaller 25 scale, the shape of the blank from which the main part of the bottle is made; and Fig. 4 is a top view of the stopper.

The main part of the bottle, as herein shown, is composed of a single piece of paper-board 30 or blank cut into the shape represented in Fig. 3. The bottom of the bottle is formed by superimposing the projecting portions 2 3 5 7 of the blank. The part 4, at one end of the blank, laps upon the face of the portion 8, constituting one side of the bottle. This blank is not 35 of my invention, and instead of it I might employ any other suitably-shaped blank to constitute the side walls, *e*, and bottom *e'*, of the bottle, or I might mold the same, in square or 40 circular form, from paper-pulp in a proper machine.

At the upper end of the bottle, and within its sides *e*, I have added, as I prefer to do, a re-enforcing piece, *b*.

The top *e* of the bottle, provided with a 45 suitable central hole or passage for the reception of the stopper, is composed of a thick piece of card-board, preferably one-eighth of an inch or more in thickness, shouldered about its 50 edges, as at 6, to rest upon and extend within the bottle-sides, as in Fig. 2, and within the re-enforce *b*. This bottle and top, united at its

seams and made water-proof by a suitable wa-
ter-proof mixture, cement or varnish, so as to
enable it to resist the passage of a liquid 55
through it, may subsequently be covered ex-
ternally with paper, as at *d*, to ornament it,
and it may, if desired, be coated and covered
internally with a water-proof film or paper.

The cement between the outer covering, *d*, 60
and paper *a* may be water-proof or water-re-
pellent.

The stopper is composed of a hollow or tubu-
lar neck, *f*, and a square or many-sided piece 65
of card-board, *g*, recessed or shouldered to hold
the tubular neck or collar *f*, as shown in Fig. 2.
This stopper is covered externally with paper,
as at *h*, and made water-proof. The exterior
of the neck *f* is made conical. The neck *f*, as 70
it is inserted within the correspondingly-shaped
opening in the top, is turned a little axially,
thus setting the stopper very firmly in the said
top, the neck springing a little and assisting
materially in forming a close liquid-tight joint. 75
The square or many-sided head *g* of the stop-
per enables it to be grasped firmly when turn-
ing or twisting the stopper into or removing
it from the top *c*.

To produce a practical bottle of paper the top must be not less than one-eighth of an inch 80
in thickness, and preferably somewhat more,
or else the pressure between the stopper and
top will be insufficient to cause the same to
adhere or remain in close contact; and, further,
a paper bottle with its top only as thick as 85
would be the sides of a practical bottle would
not afford sufficient rigidity to permit the stop-
per to be inserted or turned therein as closely
as needed.

I claim—
90
The paper bottle having the thicker paper-
board top to fit the top of the side pieces, and
provided with an opening for a stopper, com-
bined with the paper stopper having a tubular
neck and many-sided or angular head *g*, as and 95
for the purpose set forth.

In testimony whereof I have signed my name
to this specification in the presence of two sub-
scribing witnesses.

ALPHONSO C. WILLIAMS.
